UNITED STATES PATENT OFFICE.

WILLIAM SELLERS PICKERING AND HARRY GROVE, OF EXETER,
ENGLAND.

CENTER VALVE FOR GAS-PURIFIERS.

SPECIFICATION forming part of Letters Patent No. 761,992, dated June 7, 1904.

Application filed April 1, 1904. Serial No. 201,165. (No model.)

To all whom it may concern:

Be it known that we, WILLIAM SELLERS PICKERING, a resident of 4 School road, St. Thomas, Exeter, and HARRY GROVE, a resident of Ivydene, Pinhoe road, Exeter, in the county of Devon, England, citizens of Great Britain, have invented certain new and useful Improvements in and Relating to Center Valves for Gas-Purifiers, of which the following is a specification.

This invention relates to center valves for gas-purifiers, and particularly to the "Pickering" valve, which is the subject-matter of the prior British patent, No. 7,087, March 22, 1902, and has for its object while providing a valve of simple construction for direct attachment to the purifier-casing and while obviating the employment of independent connections therewith to provide a valve in which 20 separate controlling-valves for the inlet and outlet of each of the compartments of the purifier are dispensed with and in which the course of the gases is altered as required by hydraulic means.

According to the invention the inlet and outlet chambers pertaining to the respective compartments of the purifier are provided with a partition which divides the respective chambers into two compartments, one of 30 which is open to the main inlet-chamber or the main outlet-chamber, as the case may be, while the other is open to a connecting chamber or hood by means of which communication is made between the outlet of one purifier compartment and the inlet of the next in the series, which connecting chamber or hood is also provided according to the invention with a vertical partition. The partitions in the respective inlet and outlet chambers and in the 40 connecting hoods or chambers extend short of the full height of the chambers, so that thus a communicating aperture is provided at the lower part thereof. Means are provided for the admission of a quantity of water or other liquid to fill the lower part of the inlet and outlet chambers or to fill the lower part of the connecting hoods or chambers when it is respectively desired to cut off communication between the inlet and outlet chamber of the

respective compartments and the main inlet and main outlet chambers and when it is desired to cut off communication between the outlet pertaining to one purifier-compartment and the inlet of the next. The admission and discharge of water or other liquid from the inlet, outlet, and connecting chambers may be effected by any suitable and convenient means, and any ordinary self-acting valves may be provided for limiting the amount of water supplied to the respective chambers, or self-acting overflow devices or siphons may be provided for the same object.

The invention is illustrated in the accompanying drawings, in which—

Figures 1 and 2 are sectional plan and sectional elevation on the line *a b*, Fig. 1, respectively, of one form of center valve provided according to the invention. Fig. 2^a is a plan view of a first compartment-purifier to which the valve illustrated in Figs. 1 and 2 is shown as applied. Figs. 3 and 4 are sectional plan and sectional elevation on the line *a b*, Fig. 3, respectively, of a modified form of center valve.

In carrying the invention into effect, as illustrated in Figs. 1 and 2 of the accompanying drawings, in its application on the under face of a purifier having four compartments we provide the main valve-casing *a* of a rectangular form, the main part of the casing forming the main inlet-chamber *b*, while a diagonal tubular casing *c* is provided within the main casing to serve as the main outlet-chamber. Combined inlet-chambers *e' e' e' e'* and outlet-chambers *d' d' d' d'* are provided upon each of the four sides of the main casing *a*, which chambers respectively communicate with the main inlet-chamber *b* and main outlet-chamber *c* by apertures *y*, provided toward the top of the vertical walls of the main inlet-chamber *b*. It will be understood that the valve is placed below the purifying-chamber and that the combined inlet and outlet chambers communicate with the compartments of said purifying-chamber in the manner indicated in Fig. 2^a. In this figure A A designate the partition-walls of the purifier, and it will be seen that inlet-chamber *e* and outlet-chamber *d*

ber d^3 both communicate with one of the purifying-chambers through the ports indicated at e^x and d^x , and so on. Each inlet and outlet chamber, such as e and d , is provided with a vertical partition x , which stops short of running the full height of the chamber, so as thus to provide a sufficient space toward the bottom of the chambers for communication between the respective sides of the partition.

10 The associated inlet and outlet chambers on each side are connected together by a connecting chamber or hood j , within which a vertical partition j' is also provided, which falls short of the full height of the chamber and provides a space toward the bottom for communication between each compartment of the connecting hood or chamber. Communication is made between the respective inlet and outlet chambers and their respective hoods or

15 chambers by apertures w , provided toward the top of the walls which separate them. It will thus be understood that on water being supplied to the associated inlet and outlet chambers the water rises above the lower edge of the dividing-partition x , so that thus communication with the main inlet and main outlet chambers, respectively, is cut off, and the gases passing into one outlet-chamber thus pass through to the corresponding connecting

20 hood or chamber j and under the dividing-partition j' thereof into the inlet-chamber of the next purifier-compartment in the series. When it is desired to cut out one of the purifier-compartments, it is only necessary to flood

25 two connecting-hoods, together with the inlet and outlet chambers of the compartment to be cut out, and discharge the inlet-chamber of the compartment to be worked first and the outlet-chamber of the one last worked, so that

30 thus the purified gas instead of passing through the compartment comes direct into the main outlet-chamber and unpurified gas passes from the main inlet-chamber to the inlet-chamber of the next compartment of the

35 series.

40 The invention is not confined to any particular arrangement of the respective inlet and outlet chambers or of the connecting hoods or chambers.

45 According to a modification as illustrated in Figs. 3 and 4, the connecting chamber or hood j may be arranged between its respective inlet and outlet chambers, such as e^3 and d^3 , and may be provided with a partition j' at right angles to the partition in the said inlet and outlet chambers instead of arranging the connecting chamber or hood j on the side of the said inlet and outlet chambers and instead of providing the dividing-partition in line or parallel with the wall dividing the inlet and out-

let chambers, as in the modification hereinbefore described with reference to Figs. 1 and 2.

5 A center valve, as hereinbefore described, may be provided in connection with a controlling tap-cock, by means of which water or other liquid may be supplied to and discharged from the respective inlet and outlet chambers and supplied to and discharged from the connecting-chambers by the operation of one operating-handle. The construction of such a controlling tap-cock and the overflow devices may be such as is very well known.

65 The invention is not limited to the provision of partitions in the manner hereinbefore described, as the means of sealing the respective compartments of the inlet, outlet, and connecting chambers may be modified substantially to meet the requirements of different forms of purifier, and similarly the arrangement of the said chambers may be modified 70 without departing from the invention as broadly defined.

75 What we claim as our invention, and desire to secure by Letters Patent, is—

80 1. A hydraulic center valve for gas-purifiers comprising main inlet and outlet chambers, a plurality of combined inlet and outlet chambers having communication with the main inlet and outlet chambers respectively and communicating also with the compartments of the purifier, and partitions in said combined inlet and outlet chambers having ports at the bottom whereby by flooding any of said chambers the ports thereof may be closed, substantially as described.

85 2. In a hydraulic center valve for gas-purifiers the combination with a plurality of purifying-chambers, of a main inlet and a main outlet chamber, a series of pairs of subordinate inlet and outlet chambers, communicating respectively with main inlet and outlet passages, passages placing each purifying-compartment in communication with the inlet-passage of one pair and the outlet-passage of the succeeding pair, partitions in said pairs of inlet and outlet passages subdividing them into chambers communicating at the lower part which communication may be closed with liquid and passages connecting the inlet and outlet chambers of each pair, substantially as described.

90 In testimony whereof we have signed our names to this specification in the presence of two subscribing witnesses.

95 WILLIAM SELLERS PICKERING,
HARRY GROVE.
